CLAIM

(21) Appl. No.: **29/169,488**

The ornamental design for an aerosol dispenser cap, as shown and described.

(22) Filed: **Oct. 21, 2002**

DESCRIPTION

(51) LOC (7) Cl. **09-07**

FIG. 1 is a perspective view of the aerosol dispenser cap of the claimed design;

(52) U.S. Cl. **D9/448**; D9/447; D9/445; D9/444

FIG. 2 is a front elevational view of the article shown in FIG. 1;

(58) Field of Search D9/300, 434-454; D19/43; 215/336, 200; 222/538, 182, 530; 220/915, 735; 239/232, 337

FIG. 3 is a rear elevational view of the article shown in FIG. 1;

(56) **References Cited**

FIG. 4 is a side elevational view of the article shown in FIG. 1, the opposite side view being a mirror image thereof;

U.S. PATENT DOCUMENTS

FIG. 5 is a top plan view of the article shown in FIG. 4; and,

4,305,528 A	12/1981	Craig
4,664,300 A	5/1987	Strickland
4,819,838 A	4/1989	Hart, Jr.

FIG. 6 is a bottom plan view of the article shown in FIG. 4. The broken lines in the Figures are for illustrative purposes only and form no part of the claimed design.
